UNITED STATES PATENT OFFICE.

IDA LA FERTÉ, OF DETROIT, MICHIGAN.

DESIGN FOR A PLATE.

SPECIFICATION forming part of Design No. 26,024, dated September 15, 1896.

Application filed July 20, 1896. Serial No. 599,980. Term of patent 14 years.

To all whom it may concern:

Be it known that I, IDA LA FERTÉ, a citizen of the United States, residing at Detroit, in the county of Wayne and State of Michigan, have invented and produced a new and original Design for a Plate, of which the following is a specification, reference being had therein to the accompanying drawings, in which—

Figure 1 is a central section of a plate embodying my invention. Fig. 2 is a perspective view looking from the under side.

A is a thin plane or flat disk circular in plan. On its upper edge is a marginal beading B, the inner face of which merges by the curved line C into the upper face of the disk, the outer face of which extends vertically down in line with and forms the edge of the disk. On the under face of the disk, which,

like the upper face, is flat, (shown as about 20 a quarter-way from the edge,) is a downwardly-extending circular beading, semicircular in cross-section, as shown in Fig. 1.

The leading feature of the design is the flat circular disk with the upwardly-extending marginal beading and the intermediate downwardly-extending beading on the under side.

What I claim as my invention is—

The design for a plate herein described and shown.

In testimony whereof I affix my signature in presence of two witnesses.

IDA LA FERTÉ.

Witnesses:

M. B. O'DOGHERTY,
WALTER H. POTTER.
